(57) **CLAIM**

The ornamental design for firearm grip as shown and described.

DESCRIPTION

FIG. 1 is an isometric view of a portion of a firearm grip, showing our new design;

FIG. 2 is a side detail view of part of the portion of the firearm grip;

FIG. 3 is a rear view of the part of the portion of the firearm grip; and,

FIG. 4 is an isometric view of a portion of another firearm grip.

The dot-dash broken line represents an unclaimed boundary of the claimed design. The broken lines depicting the remainder of the firearm components show features that form no part of the claimed design.
